US00D519803S

(12) **United States Design Patent** (10) **Patent No.:** **US D519,803 S**
(45) **Date of Patent:** **** May 2, 2006**

(54) **PORTION OF A PAIR OF PLIERS JAWS**

(75) Inventor: **Hollan A. Tsuda**, Portland, OR (US)

(73) Assignee: **Leatherman Tool Group, Inc.**,
Portland, OR (US)

(**) Term: **14 Years**

(21) Appl. No.: **29/220,911**

(22) Filed: **Jan. 7, 2005**

(51) **LOC (8) Cl. 08-05**

(52) **U.S. Cl. D8/52; D8/4**

(58) **Field of Classification Search** D8/4-5,
D8/57-58, 52, 105; 7/128; 81/427.5

See application file for complete search history.

(57) **CLAIM**

The ornamental design for a portion of a pair of pliers jaws, as shown and described.

DESCRIPTION

FIG. 1. is an isometric view from the upper right front of a portion of a pair of pliers jaws, including my new design; FIG. 2. is an isometric view from the lower left rear of the portion of a pair of pliers jaws shown in FIG. 1;

FIG. 3 is a top plan view thereof;

FIG. 4 is a right side elevational view thereof;

FIG. 5 is a bottom plan view thereof; and,

FIG. 6 is a left side elevational view thereof.

The broken lines immediately adjacent the shaded areas represent the bounds of the claim and all other broken lines are for illustrative purposes only. None of the broken lines form a part of the claimed design.

1 Claim, 2 Drawing Sheets
